United States Patent Office.

JOHN E. PARKER, OF MERIDEN, CONNECTICUT.

Design No. 3,140, dated July 28, 1868.

DESIGN FOR A DRAWER-PULL.

The Schedule referred to in these Letters Patent and making part of the same.

TO ALL WHOM IT MAY CONCERN:

Be it known that I, JOHN E. PARKER, of Meriden, in the county of New Haven, and State of Connecticut, have invented a new Design for Drawer-Pull; and I do hereby declare the following, when taken in connection with the accompanying drawing, and the letters of reference marked thereon, to be a full, clear, and exact description of the same, and which said drawing constitutes part of this specification, and represents a front view.

This invention relates to a design for a cast-metal handle to be attached to a drawer-front for the purpose of opening the drawer, and the design consists in the configuration and ornamentation of the outer surface.

A is the shell, secured by screws at α . From around the said screw-holes springs a leaf turning up and terminating near the centre, both ends corresponding, the lower edge beaded, and terminating near the screw-holes in a corresponding ornamentation.

I do not wish to be understood as broadly claiming a design for a cast-metal drawer-pull of shell-shape, as such are common and well known, of various configuration and ornamentation, but

What I claim, is—

The design for a drawer-pull, herein described and illustrated.

JOHN E. PARKER.
